WEFT TENSIONING AND INSERTING DEVICE
FOR GRIPPER SHUTTLE LOOMSHeinrich Schäffer, Werther, near Bielefeld, Germany, as-
signor to C. A. Delius & Söhne, Bielefeld, Germany,
a firm of GermanyFiled Aug. 18, 1960. Ser. No. 59,430
10 Claims. (Cl. 139—126)

This invention relates to a loom in which the weft 10
yarn is withdrawn from stationary pirns for insertion
into the shed.

In a known type of loom of this kind sufficient weft
yarn for two picks is withdrawn from pirns located on
both sides of the loom. The ends of the picks are gripped
in alternation by a nipper shuttle which consecutively
traverses the shed in both directions and draws the yarn
into the shed alternately from the right and the left of
the loom to the effect that picks consecutively withdrawn
from each side of the loom form loops around the edge
of the fabric and produce a firm selvedge. One dis-
advantage of a loom of this kind is that the picks do
not remain under tension when they are released by the
nipper. Consequently the picks tend to draw back into
the shed and to cause dislocations and irregularities in
the weave, for instance in the form of eyes in the weft.
The absence of tension in the pick may also cause the
weft stop motion to operate and the loom to be stopped
without cause.

In another known loom of this type the weft yarn
for forming either two or only one pick is likewise with-
drawn for pirns on both sides of the loom. In this loom
the ends of the picks are also gripped by a nipper shuttle
and drawn into the shed alternately from the right and
the left, so that consecutive picks in the weave are de-
rived from the right and the left hand side of the loom.

In order to maintain the picks under tension when
they are released by the shuttle, suction openings are
located on the face of the sley of this loom on both
sides of the fabric at a given distance therefrom, the
ends of the picks being drawn into the openings by the
suction effect. For retaining the ends of the picks, gripping
slides are provided and cutters later cut off the
ends of the picks. This loom likewise suffers from
several drawbacks. The ends the picks are not ex-
posed to the suction effect until the nipper shuttle has
moved past the openings. It is then already too late
for a decisive effect on the picks to take place because
by then the shed has already closed. Furthermore, in
this loom, there is considerable waste of material and
the cutting off of the ends of the picks which project
from the sides of the fabric causes additional work.
Finally, the provision of the suction orifices and of
gripping slides for cooperation therewith as well as of
the cutters cause such a loom to be of relatively complex
construction.

The loom contemplated by the present invention is like-
wise one in which the necessary weft yarn for two picks
is withdrawn from pirns on both sides of the loom, the
picks being inserted into the shed by a shuttle containing
no pirn alternatively from the right and the left, and in
which the picks are subjected to suction for keeping them
under tension as they slip out of the shuttle. In the
contemplated loom it is the object of the present invention
to overcome the disadvantages inherent in known
types of loom, more particularly to ensure that the picks
will pull straight in a desirable manner when they are
released by the shuttle. To this end the invention pro-
poses to equip the loom at both edges of the loomed
fabric, for the purpose of subjecting the picks to a suc-
tion effect, with slidably displaceable suction pipes which

2

enter the shed as the shuttle approaches, intercept the
yarn by their suction as it slips from the shuttle and
then withdraw from the shed whilst retaining the yarn.

In a preferred form of construction of the invention
5 the front of the sley below the race is fitted with a hori-
zontal rail upon which the suction pipes are mounted
on slidable sleeves, a helical spring interposed on the
rail between the said sleeves of the suction pipes urging
the pipes apart in opposite directions, eccentrics being
provided for controlling the motions of the suction pipes
through draw means attached to the slidable sleeves.

According to the invention the suction effect generated
by the suction pipes for holding and straightening the
picks is preferably of short duration. With reference to
15 the particular form of construction of the suction pipes,
the invention envisages various embodiments which can
be used according to their suitability for different kinds
of weft material. In order to adapt the suction pipes
20 to weft yarns of different kinds they may be of multipart
construction and detachably affixed to the slidable sleeves.

Since in the novel loom the suction pipes enter the
shed when the shuttle approaches for intercepting the
picks before the shed closes, they ensure that the picks
25 are correctly entrained and pulled straight. This is a
matter of particular importance if the loomed materials
are smooth, elastic, or of a kind which easily accepts
an electrostatic charge, since in such materials the picks
30 are particularly liable to pull back into the shed and to
give rise to irregularities in the weft. The fact that in
the proposed loom the suction pipes enter the shed when
the shuttle approaches and intercept the yarn as it slips
35 from the shuttle has the further advantage that the ends
of the picks need not be so long as to project from the
edge of the fabric and can be just long enough to end
at the selvedge. This provides an economy in material
40 and also saves the time otherwise expended in cutting
off the loose ends of the picks by a special subsequent
operation. Moreover, the proposed loom does not re-
quire the provision of special gripping slides and of cut-
45 ting devices cooperating with the suction pipes for the
purpose of retaining and cutting off the ends of the picks,
such devices introducing complexities into the construc-
tion of the loom besides preventing the employment of
temples.

The relevant parts of the loom according to the in-
vention are illustratively and partly schematically shown
in the accompanying drawings which also show the man-
ner in which the loom operates and the nature of the
50 fabric which can be produced. In the drawings:

FIG. 1 is a plan view of a fabric produced on the
loom,

FIGS. 2 to 7 schematically illustrate the manner in
which the loom functions,

FIG. 8 is an illustration of the shuttle used in the loom,
55 with a pick and a suction pipe seen from above,

FIG. 9 is the sley of the loom with suction pipes
mounted thereon as well as the means for supporting and
actuating the suction pipes, seen in front elevation,

FIGS. 10 to 12 are three alternative embodiments of suc-
60 tion pipes seen from the front,

FIG. 13 is another embodiment of the suction pipe
and of the means of mounting the same, seen from the
front with respect to the loom.

In the diagram of the fabric shown in FIG. 1 the
65 warp ends are indicated by *a*, the picks inserted from the
left hand side of the loom by *b*₁ and those inserted from
the right hand side of the loom by *b*₂.

On both sides of the loom there are provided in con-
70 ventional manner yarn gripper means, with a yarn guide
20, as well as two grippers 21 and 22 which alternately
grip the weft yarn *b*, i.e. the picks *b*₁ and *b*₂. Further-

more, there is provided, on each side of the loom, likewise in conventional manner, a pick length measuring device with revolving projections 23 and 24 which entrain the weft yarn *b* at the grippers and withdraw the same, as well as a shear 25 for severing the yarn lengths for forming the picks *b*₁ and *b*₂ from the supply of weft yarn *b*.

FIGS. 2 to 7 illustrate the manner in which the loom functions by showing the operations which are consecutively performed on the right hand side of the loom. As shown in FIG. 2 the end of the weft yarn *b* is gripped in an outside gripper 21 and presented by a yarn guide 20 to an inner open gripper 22. As shown in FIG. 3 the weft yarn extending between the two grippers 21 and 22 is now entrained by a projection 23 of the pick length measuring means and a length of yarn is withdrawn which corresponds with the length of the first pick *b*₂ the yarn during said withdrawal running through the open inner gripper 22. When the length of the first pick *b*₂ has thus been measured, as shown in FIG. 4, the yarn is retained by the closure of the inner gripper 22 and the outer gripper 21 opens for releasing the free end of the pick. The yarn guide 20 now swings the yarn *b* from the inner gripper 22 back to the outer gripper 21 which is open. As shown in FIG. 5, the first pick *b*₂ is then inserted into the shed by the shuttle 26. As shown in FIG. 6, the yarn *b* which now extends between the two grippers 21, 22 is entrained by the second projection 24 of the pick length measuring means and the length required for the second pick *b*₂ from the right hand side of the loom is withdrawn, the yarn *b* running through the open outer gripper 21. As soon as the yarn *b* has again been gripped by the outer gripper 21 the yarn *b*₂ is cut off at the rear end of the second pick *b*₂ from the right hand side of the loom by shear 25 and the severed portion of yarn *b*₂ is finally released by the inner gripper 22 in the manner shown in FIG. 7. The portion of yarn forming the second pick *b*₂ from the right hand side of the loom is then inserted by shuttle 26.

The left yarn *b* unwinds from the cross wound pirns on both sides of the loom and is conducted by suitable guide means to the yarn gripping and pick length measuring devices through a gentle yarn brake 27. In view of the distance between the yarn grippers and the selvedges of the fabric, different lengths of yarn *b* are withdrawn for forming the two picks *b*₁ and *b*₂; the said picks *b*₁ and *b*₂ each comprising a first and a second pick which are inserted from the same side of the loom. The second pick is shorter than the first pick by twice the distance between the yarn gripping means and the selvedge.

The shuttle 26 illustrated in FIG. 8 is a flat member with a cavity 28 opening along a portion of its length in the upward direction. The forward side wall likewise has a recess 29 which opens in the upward direction. Finally, the shuttle is provided with a yarn entraining member 30 of wing-like shape, each wing pointing in one of the longitudinal directions of the shuttle and being located inside the cavity 28 in the region of the recess 29.

Fitted to the front face of the sley 31 is a guide rail 32, as shown in FIG. 9. This rail carries slideable sleeves 33 upon which suction pipes 34 are mounted. A helical spring 35 surrounding rail 32 is interposed between the slideable sleeves 33 of the suction pipes 34 in such manner as to urge the two pipes apart. Attached to the inner ends of the slideable sleeves 33 of the suction pipes 34 are draw means 36 operable by eccentrics 37 which control the motions of the suction pipes.

The suction pipes 34 illustrated in FIGS. 10 to 12 have a bevelled suction end and are so placed that their suction opening is approximately parallel with the direction of motion of shuttle 26. The suction pipe 34a shown in FIG. 10 is formed with a yarn entry slit 38 extending from the suction opening at the operative end of the pipe. The presence of this slit facilitates the entry by suction of the pick end and prevents the latter from tangling.

The suction opening of suction pipe 34b in FIG. 11 is covered with a fine mesh 39, such as metal gauze. This offers a surface upon which the yarn can rest whilst it is exposed to the suction effect. A similar effect is produced by the third suction pipe 34c illustrated in FIG. 12. The suction opening of this pipe is provided with a cover plate 40 with a central orifice 41 at its leading end and two symmetrically disposed orifices 42 towards the rear end. The two last described suction pipes 34b and 34c are especially suitable for picks of medium and fine gauge.

The suction pipe 34d, shown in FIG. 13, tapers towards the suction end and its tapering portion 43 extends approximately parallel with shuttle 26. On the side of the tapering portion 43 facing the shuttle 26 are a number of suction orifices 44 which form a linear row. Owing to the large number of small openings 44 this suction pipe 34d has a particularly intense suction effect on the ends of the picks. Moreover, the wall of the tapering portion 43 offers a surface upon which the end of the pick can rest whilst it is held by the suction.

Although not specially shown in the drawing, the suction pipes 34 are of multipart construction and the portion provided with the suction opening or openings is detachably affixed to the supporting slideable sleeve 33. To this end, the sleeves 33 are fitted with clamping jaws 45 and screw means 46 for locating the end portion of the suction pipes 34 on the sleeves 33.

When the suction pipes 34 enter the shed during the approach of shuttle 26 they assume a position inside the shed in relation to shuttle 26 which is illustratively and diagrammatically shown in FIG. 8. They remain in this position by moving out of the shed together with the shuttle 26. The end of the pick *b*₂ which slips from the shuttle 26 is held captive by the suction of pipe 34 and is therefore extended until it is straight.

Having thus fully described my invention, what I claim as new and desire to secure by Letters Patent of the United States is:

1. In a loom of the type in which lengths of weft yarn for two picks are withdrawn from pirns on both sides of the loom, the ends of the picks being inserted into the shed alternately from the right and the left of the loom by means of a pirnless shuttle riding upon a sley, and the ends of the picks upon being released by the shuttle are subject to suction to hold the picks under tension, the improvement which comprises, suction pipes slidably mounted at each side of the loom for movement into and out of the warp shed, and means to move each suction pipe into the shed to meet an approaching shuttle and withdraw the suction pipe in unison with the shuttle, whereby the pick ends will be drawn to the suction pipes as they slip from the shuttle and be held under tension as the suction pipes withdraw from the shed.

2. A loom as claimed in claim 1 wherein, the suction pipes have suction ends which are bevelled to provide suction orifices, and the suction pipes are mounted with their suction orifices parallel to the path of movement of the shuttle along the sley.

3. A loom as claimed in claim 2 wherein, the suction pipe is notched from the suction orifice to provide a yarn end entry notch extending from the orifice.

4. A loom as claimed in claim 2 wherein, the bevelled suction orifices are covered with a mesh-like material.

5. A loom as claimed in claim 2 wherein, the bevelled orifices of the suction pipes are closed by cover plates having central openings at their leading ends and two openings symmetrically disposed on opposite sides of the suction pipe axis at the rear ends of the cover plates.

6. A loom as claimed in claim 1 wherein, the suction pipes have suction ends and taper towards their suction ends, the suction pipes being mounted with their tapering ends generally parallel to the path of movement of the shuttle along the sley, and the tapering ends each having a wall adjacent the shuttle path with a row of adjacent suction orifices.

7. A loom as claimed in claim 1 wherein, the suction pipes have detachable suction end portions.

8. A loom as claimed in claim 1 wherein, the suction hold of the suction pipes upon the picks is of short duration only.

9. In a loom of the type in which lengths of weft yarn for two picks are withdrawn from pirns on both sides of the loom, the ends of the picks being inserted into the shed alternately from the right and the left of the loom by means of a pirlless shuttle riding upon a sley, and the ends of the picks being released by the shuttle are subject to suction to hold the picks under tension, the improvement which comprises, a horizontal guide rail mounted upon the sley, a sleeve slidably mounted upon the rail adjacent each end of the sley, suction pipes carried by the sleeves, a spring surrounding the guide rail between the sleeves urging the sleeves apart, and an eccentric in operable relation to each sleeve to move the sleeve along the guide rail to move the suction pipe carried by the sleeve into the warp shed to meet an approaching shuttle and permit withdrawal of the suction pipe from the shed under the influence of the yieldable means, whereby the pick ends will be drawn to the suction pipes as they slip from the shuttle and be held under tension as the suction pipes withdraw from the shed.

10. In a loom of the type in which lengths of weft yarn 25

for two picks are withdrawn from pirns on both sides of the loom, the ends of the picks being inserted into the shed alternately from the right and the left of the loom by means of a pirlless shuttle riding upon a sley, and the ends of the picks upon being released by the shuttle are subject to suction to hold the picks under tension, the improvement which comprises, a horizontal guide rail mounted on the sley, a sleeve slidably mounted upon the rail adjacent each end of the sley, suction pipes carried by the sleeves, a spring surrounding the guide rail between the sleeves urging the sleeves apart, and an eccentric in operable relation to each sleeve to move the sleeve along the guide rail to move the suction pipe carried by the sleeve into the warp shed to meet an approaching shuttle and permit withdrawal of the suction pipe from the shed in unison with the shuttle under the influence of the spring, whereby the pick ends will be drawn to the suction pipes as they slip from the shuttle and be held under tension as the suction pipes withdraw from the shed.
